UNITED STATES PATENT OFFICE.

GEORGE M. SHEFFER, OF EMLENTON, PENNSYLVANIA.

CURRENT-MOTOR.

1,201,882.

Specification of Letters Patent. Patented Oct. 17, 1916.

Application filed September 25, 1914. Serial No. 863,578.

To all whom it may concern:

Be it known that I, GEORGE M. SHEFFER, a citizen of the United States, and a resident of Emlenton, in the county of Venango and State of Pennsylvania, have made certain new and useful Improvements in Current-Motors, of which the following is a specification.

My invention is an improvement in current motors and has for its object to provide a device of the character specified, mounted on a float in such manner that it may be raised or lowered with respect to the float to provide for variations in water conditions, and wherein the support for the motor is provided with mechanism capable of connection to and disconnection from the current motor for operating the said motor in a direction to propel the boat or scow, the said mechanism being releasable from the current motor, and wherein a speeding up connection is provided between the current motor and the mechanism to be driven, the said mechanism being arranged to be connected to and disconnected from the current motor, and wherein guiding mechanism is provided for the motor support to guide the same during its movement from place to place.

30 A further object is to provide a new and improved form of vane, so arranged that it will utilize to the fullest possible advantage the impelling force of the water.

In the drawings Figure 1 is a top plan view of the improved motor, Figs. 2 and 3 are sections on the lines 2—2 and 3—3 respectively of Fig. 1, Fig. 4 is a partial perspective view of the motor supporting frame showing the adjusting mechanism, and Fig. 40 5 is a partial perspective view of one of the vanes or blades.

The present embodiment of the invention is shown in connection with a float or scow 1, having a pointed bow 2, and having a central opening 3 extending vertically through the scow at the center thereof to provide a place for the motor proper. At the opening the scow is provided with webs 4, which form with the body of the scow a chamber 5 which extends on both sides of the scow and across the front and rear, and the air in the chamber assists in making the scow buoyant, so that it will float upon the surface.

55 Within the opening 3 of the scow an open rectangular frame is arranged, the said

frame consisting of side members 6 and end members 7 connecting the side members, and the frame is of such size that it will fit within the opening and will be movable vertically in the opening to adjust the motor to the required height. The motor proper is supported by the frame and is adjusted vertically with the frame. The motor proper consists of a front shaft 8 and a rear shaft 9, the said shafts being journaled transversely of the frame in bearings 10 on the side members, and a pair of sprocket wheels 12 is secured to each shaft near the ends thereof.

Endless sprocket chains 13 are supported by the wheels 12, it being understood that the wheels of each shaft register with the wheels of the other shaft and the chains are supported by the registering wheels. The chains at each side of the frame are connected at spaced intervals by blades or vanes, the said blades or vanes being arranged transversely of the frame and being connected with the chains at their ends. Each blade or vane comprises a plate 14 having at each end a head 15 of circular form, the plates being arranged diametrically of the heads. Each of the heads 15 is provided with an axial journal pin 16, and the pins are connected to the chains 13 in the following manner: Each of the chains 13 is composed of pairs of parallel spaced links, the adjacent pairs of links being connected at their ends by rivets 13^a, and the members of the pairs are spaced apart by arbors 13^b, the said arbors being arranged on the rivets between the members of the pairs. Each journal pin 16 takes the place of a rivet, the said pins being passed through the openings at the meeting end of the pairs of links, and a sleeve or arbor 17 is arranged on the journal pin between the members of the pairs of links. At least one of the pins of each blade or vane is rigid with one pair of links in order that the blade will be held in a certain definite position with respect to the chain, that is, perpendicular to the upper and lower runs of the chain. A cotter pin 18 is passed through the journal pin outside of the outermost links to hold the parts in place, and the blades or vanes are so arranged that the plates 14 will occupy a vertical position on the upper and lower runs of the chains, as shown more particularly in Fig. 2.

It will be evident that when the current

of water strikes the blades or vanes 14 they will be moved in the direction of flow of the current to move the chains and to rotate the shafts 8 and 9. It will be understood 5 that the frame 6-7 is so arranged that the vanes on the lower run of the endless chains 13 will enter the water, while the vanes on the upper runs of the chains will be above the level of the water.

10 Mechanism is provided for supporting the frame 6-7 and for adjusting the same vertically to adjust the motor. The said mechanism comprises threaded rods or shafts 19 arranged at the corners of the 15 frame 6-7, each shaft or rod being threaded through a nut 20 held in the frame at the corner thereof. Each rod or shaft is provided at its lower end with a stop in the form of an annular rib 21 and a diametrical opening 22 is provided in each shaft or rod below the stop. The lower end of each shaft or rod passes through an opening in a lug 19^a extending into the opening 3 from the adjacent web 4, and the 20 downward movement of the shaft or rod is limited by the stop 21. A pin may be passed through the opening 22 below the lug to prevent upward movement of the shaft or rod, and the four shafts or rods 25 and the frame 6-7 as well as the motor are thus supported by the lugs 19^a.

Each of the shafts 19 has a sprocket wheel 23 secured thereto near its upper end and the wheels at each end of the frame 6-7 35 are connected by a sprocket chain 24. The shafts or rods 19 at one side of the frame 6-7 are provided with worm wheels 25 at their upper ends and above the sprocket wheel, and each worm wheel is engaged by 40 a worm 26 on a shaft 27 arranged longitudinally of the frame on the upper surface of the scow, journaled in bearings 28 on the said upper face. At one end, preferably the front end, the shaft 27 is provided with 45 a crank 29. It will be evident that when the shaft is rotated by means of the crank, the rods 19 will all be rotated in one direction or the other, depending upon the direction of movement of the shaft. When the 50 rods are rotated the frame 6-7 will be moved upwardly or downwardly, the shafts or rods being supported by the scow for rotation. The frame and the motor may thus be adjusted to any desired height, and 55 when at the proper height the worm gear connection 25-26 will hold the parts in adjusted position. A countershaft 30 is arranged transversely of the scow directly above the shaft 9, and the said shaft is journaled in bearing brackets 31 secured to the frame, and the brackets are of sufficient height to hold the shaft spaced above the upper face or surface of the frame. Gear 60 wheels 32 are journaled loosely on the shaft near each end thereof, and each gear wheel 65

carries one section 33 of a clutch at the inner end of its hub, the other section 34 of the clutch being feathered upon the shaft as indicated at 35. The arrangement is such that the gear wheels 32 may be connected to the shaft 30 or disconnected therefrom at will. 70

Mechanism is provided for simultaneously connecting and disconnecting the clutch sections, and the said mechanism 75 comprises a lever 36 pivoted to a bracket 37 secured to the boat or scow in rear of the opening 3. The lever 36 is pivoted to the bracket near one end of the lever, and links 38 connect the lever with the adjacent movable clutch sections 34. Each link 38 is pivoted to the lever at one end, and the other end of each link has a fork whose arms 39 engage an annular groove in the adjacent clutch section 34. The lever 36 is pivoted to the bracket 37 as indicated at 40 and the connections of the link 38 with the lever are on opposite sides of the pivotal connection. The lever is provided with the usual latch mechanism 41, which 80 co-operates with a toothed quadrant 42 rigid with the bracket 37 for holding the lever in adjusted position. 85

When the lever is in the position shown in Fig. 1, both gear wheels 33 are clutched to the shaft, and the said shaft will be rotated by the motor, the shaft being connected to the motor by means of gear wheels 43 secured to the shaft 9 near each end thereof and meshing with the adjacent gear wheel 100 30. Thus when the motor is in operation with the shaft 30 connected to the gear wheels 33, the said shaft 30 will be rotated and power is taken from the shaft 30 indirectly. Another shaft 44 is journaled on 105 the boat or scow in front of the opening 3 in bearing brackets 45, and this shaft is provided with a pulley 46 which is connected by means of a belt 47 with a pulley 48 on the shaft 30. The pulley 48 is of larger 110 diameter than the pulley 46, so that the shaft 44 will be rotated at a higher speed than the shaft 30 when the motor is in operation. 115

It is obvious that the power might be taken directly from the shaft 30 or directly from the shaft 44, but it is desirable to insert speeding up mechanism between the generator 48 to be operated and the motor, and this speeding up mechanism is constituted in part by the belt 47 and its connections. Another pulley 49 is secured to the shaft 44, and a belt 50 connects the pulley 49 with a pulley 51 on the generator 52. The pulley 49 is of larger diameter than the pulley 51, so that the speed is still further increased by this connection. 120

It will be obvious that when the frame 6-7 has been adjusted to the proper height and the gear wheels 33 are connected to the 125 130

shaft 30, the motor will operate, driving the shaft 30 and this shaft, through the speeding up mechanism constituted by the belts 47 and 50 and connected parts, will cause the generator to rotate at a greatly increased speed. Thus the power of the current may be utilized by transforming this power into electrical energy at the generator and presenting the power in the best possible form for use or for transmission to other points.

It is often desirable to move the motor from place to place and mechanism is provided on the boat or scow for operating the motor to move the boat or scow from place to place, the said mechanism being capable of release from the motor when the boat has reached its destination. The said mechanism comprises a motor 53, a liquid fuel engine in the present instance, and the motor is arranged on the bow of the boat with its shaft 54 parallel with the long axis of the boat. A bevel gear 55 is secured to the shaft 54, the said shaft being extended to a point adjacent to the shaft 44. The motor shaft is supported by a bearing 56 on the boat or scow adjacent to the shaft 44, and the bevel gear 55 meshes with a bevel gear 57 feathered on the shaft 44 as indicated at 58. The hub 59 of the bevel gear 57 is annularly grooved and the groove is engaged by the arms 60 of a fork on one end of a lever 61. The lever is pivoted intermediate its end, as indicated at 62, on a supporting bracket 63 secured to the scow, and the lever has latch mechanism 64 co-operating with a toothed segment 65 rigid with the bracket for holding the lever in adjusted position. When it is desired to move the boat by its own power, the lever 61 is operated to move the bevel gear 57 into mesh with the bevel gear 55. As the shaft 44 is now to be driven in order that it may drive the motor, it is desirable that the generator 48 be disconnected from said shaft, and mechanism is provided for this purpose. The hub 66 of the pulley 49 carries one section of a clutch and the other section 67 of the clutch is feathered on the shaft 44 as indicated at 68. A lever 69 is pivoted intermediate its ends, as indicated at 70, to a bracket 71 on the boat and one end of the lever is forked, the arms 72 of the fork engaging the annular groove of the hub 67. The lever has the usual latch mechanism 73, co-operating with a toothed segment 44 rigid with the bracket 71 for holding the lever in adjusted position. When it is desired to disconnect the pulley 49 from the shaft 44 the lever 69 is released from the segment 74 and is swung in a direction to move the clutch section 67 away from the wheel 49. The shaft 44 may now rotate freely without affecting the generator 48, and when the said shaft is driven

by the motor 53 the current motor will be driven in a direction to move the boat or scow forwardly, the blades or vanes on the lower runs of the chains moving rearwardly, and as the said blades or vanes strike the water they will tend to push the boat forwardly.

A rudder 75 is arranged at the rear of the boat, the said rudder having journal pins 76 and 77 which engage openings in bearing lugs 78 and 79 on the rear end of the boat or scow. The journal pin 77 is extended above the boat and is provided with an angular arm 80 for convenience in oscillating the said pin to move the rudder. It will be obvious that by means of the rudder the boat may be steered or guided to the place desired.

In order to equalize the strain on the motor, the shaft 44 is connected to both ends of the shaft 30. One of the connections is by means of the pulleys 46 and 48 and the belt 47 and the other connection at the opposite end of the shafts 44 and 30 is by means of the pulley 81 on the shaft 44, 90 which is connected to a pulley 82 on the shaft 30 by means of a belt 83. The pulleys 46 and 81 are of the same size and of smaller size than the pulleys 48 and 82 which are likewise of equal size. The belts 47 and 83, 95 as well as the pulleys 46—48 and 81—82 are arranged in vertical openings 84 and 85 respectively extending longitudinally of the boat or scow, and the said openings open into the chamber 5 before mentioned. 100

The operation of the improved current motor is as follows. The shaft 44 is disconnected from the generator 48 by means of the lever 69 and the clutch sections 66 and 67. The bevel gear 57 is then moved to connect the shaft 44 with the motor shaft 54 and the motor 53 is started, the current motor being adjusted until the blades or vanes will engage the water at the required depth. The shaft 44 moves in a direction to cause the vanes on the lower runs of the chains to move rearwardly, and consequently the boat or scow will be driven forwardly and it is guided by the rudder 75. When the boat or scow has reached the desired position it is anchored or tied up in any suitable manner, and the motor 53 is disconnected from the shaft 54 by moving the bevel gear 57 out of connection with the bevel gear 55. The pulley 49 is connected to the shaft 44 by means of the lever 69 and the motor is ready for operation. 110

As the current motor moves the gear wheels 43 will, by their engagement with the gear wheels 32, rotate the shaft 30 and the motion of this shaft will be transmitted to the generator 48 at an increase of speed. The circular head 15 at the ends of the plates 14 prevent the water from spreading out laterally of the motor or longitudinally 125 130

of the plates and constrains the water to strike against the faces of the plates to thus utilize in the fullest possible manner the propelling force of the current. The 5 sprocket chain connection 24 between the shafts 19 at the ends of the boat constrain the said shafts to move together, so that the four corners of the frame 6—7 move together vertically without any twisting or 10 skewing of the frame.

It will be noted from an inspection of Fig. 3 that the gear wheels 43 are integral with the sprocket wheels 12, being at the outer side of the said wheel. The shaft 30 15 is so arranged and the wheels 32 are of such diameter that when the gear wheels 43 are in engagement with the gear wheels 32, the blades or vanes on the lower runs of the chains will dip into the water to the proper 20 depth, each blade or vane extending slightly

below the under surface of the boat, as shown more particularly in Fig. 3.

I claim:

In a current motor, endless chains arranged in spaced relation, means for supporting the chains for longitudinal movement, and a series of blades or vanes connecting the chains at spaced intervals, each blade or vane comprising a plate, a disk or head at each end of the plate, the plate being arranged diametrically of the disks or heads, each head having an axial journal pin connected with the adjacent chain, said pins connecting the links of the chain and being 25 30 rigid with the chain.

GEORGE M. SHEFFER.
